UNITED STATES PATENT OFFICE.

LOUIS H. GEBHART, OF DAYTON, OHIO, ASSIGNOR TO THE GEBHART FOLDING BOX COMPANY, OF DAYTON, OHIO, A CORPORATION OF OHIO.

BOX.

Application filed June 10, 1926. Serial No. 115,112.

My invention relates to boxes.

It is the object of my invention to provide a box which can be readily moved from collapsed flat position to assembled box form.

It is a further object of my invention to provide a corner lock which will be easily assembled, but which, when once assembled, will stay assembled and will not pull apart.

It is my further object to provide a corner lock which will not only stay locked by reason of its construction but also by reason of its special form of edges.

It is my further object to provide a folding box that will be strong, easily assembled and rigid in construction, so that the weight of the contents of the box will not so warp the box as to unlock its corners.

Referring to the drawings:

Figure 1 is an outside perspective of a locked corner;

Figure 2 is an outside elevation of a locked corner;

Figure 3 is an inside elevation of a corner showing an end wall and top in section;

Figure 4 is a section on the line 4—4 of Figure 3;

Figure 5 is a section on the line 5—5 of Figure 3;

Figure 6 is a plan view of the corner of the box in unfolded condition;

Figure 7 is a perspective from the outside of the corner showing the corner just being folded with the locking flap being inserted in the locking slit;

Figure 8 is a perspective of the corners of the top and bottom of the box which are just about to be telescoped to form a complete closed box.

Referring to the drawings in detail, 1 is the top of a box having an end wall 2 and side wall 3. For the purpose of convenience, I have not shown the other end wall and the other side wall.

The end wall, as will be seen in Figures 6 and 7 somewhat more clearly, is provided with an end flap 4 which has a diagonal locking slit 5 provided with a serrated rough edge 6 which is so corrugated as to form a catchet-like surface for frictionally engaging with the locking flap.

This locking slit starts at the corner crease which is the crease between the end flap and the end of the box 2. The locking slit proceeds from the middle point of the

crease in the end flap 4 outwardly and laterally towards the outer edge 8 of the flap.

This end flap is separated from the side wall 3 by the serrated edge 9. The side wall is provided on its end adjacent the end flap adjacent its outer margin with a locking flap 10 having a serrated edge. This locking flap is formed on one side by the cut 9 and on the other side by a serrated slit 12. The locking flap 10 has its outer edge 11 disposed inwardly of the extreme edges 13 and 14 of the side wall 3 and the end flap. The corner 15 of the locking flap is so arranged as to its distance from the corner 16 that it will pass into the slit 5 at its outer end 17 as the end flap is passed inside of the side wall 3 when the folding of the box takes place and the locking operation of the lock is executed.

As will be seen from the drawings, when the locking flap 10 enters the slit 5, it progresses until the end wall and side wall are at right angles to one another and the corner 18 of the locking flap has passed by the corner 17 of the locking slit and is hooked behind it, while the edge 9 of the locking flap 10 is in engagement with the inner corner 19 of the locking slit. There is, of course, a crease 20 between the top and side wall, as well as the crease 21 between the top and end wall 2.

When the box is in folded condition, the end flap is within the side wall with the exception of that portion of the end flap which lies outside of the diagonal locking slit, which portion is designated 22. This is on the outside of the locking flap 10.

It will be understood that, when I refer to the top of the box, when the corresponding half of the box is made, this top may become the bottom.

It will be further understood that the edges are serrated or notched, so that their corrugated surfaces will engage with one another to provide extreme frictional engagement between the paper parts to prevent disengagement of them.

It will be understood that I desire to comprehend within my invention such modifications as may be necessary to adapt it to varying conditions and uses.

Having this fully described my invention, what I claim as new and desire to secure by Letters Patent, is:

1. In a paper box, a bottom portion, a

side wall portion, an end wall portion, an end flap having a locking slit and a locking flap carried by the side wall said locking flap having a plurality of integrally formed, relatively small, evenly spaced teeth formed on the edge thereof.

2. In a paper box, a bottom portion, a side wall portion, an end wall portion, an end flap having a locking slit and a locking flap carried by the side wall, said flap and slit having their edges formed into a plurality of integral, regularly spaced teeth of relatively small size.

3. In a box, a body portion, an end wall portion, a side wall portion, an end flap portion having a diagonal locking slit and a rectangular locking flap portion on the end wall portion, said slit and locking flap portion having edges formed into a plurality of integral, regularly spaced teeth of relatively small size.

4. In a box, a top portion, an end wall, a side wall, said end wall having an end flap hinged thereto extending across the end of the side wall and having a locking slit, a locking flap formed parallel to the end flap and as a part of the side wall of the box, the edges of the locking flap and the slit being formed into a plurality of integral, regularly spaced teeth of relatively small size.

5. In a paper box having a body portion, end and side walls locked together at the corners constituting a corner lock, edges on

the locking portions thereof to resist the unlocking thereof, such edges being formed into a plurality of relatively small teeth with the ends of the teeth spaced from one another.

6. In a box, a body portion, an end wall portion, a locking flap hinged thereto extending across the end of a side wall portion, a side wall portion, a locking flap interposed between the end flap and the side wall portion, said end flap having a locking slit, and said locking flap and end flap having adjacent edges, and said locking flap and side wall portion having adjacent edges, all of the edges of said parts being formed into a plurality of small finely spaced teeth of uniform size.

7. In a paper box, a bottom portion, a side wall portion, an end wall portion, an end flap having a locking slit and a locking flap carried by the side wall, said locking slit having edges formed into a plurality of small evenly spaced uniform sized teeth.

8. In a paper box, a bottom portion, a side portion, an end wall portion, an end flap having a locking slit and a locking flap carried by the side wall, all of the exposed edges and the locking slit having edges formed into a plurality of relatively small evenly spaced teeth.

In testimony whereof, I affix my signature.

LOUIS H. GEBHART.
